UNITED STATES PATENT OFFICE.

HEINRICH HECHT AND FERDINAND SCHENKELBERGER, OF KIEL, GERMANY.

SUBAQUEOUS SOUND-SIGNAL TRANSMITTER.

Application filed May 28, 1914. Serial No. 841,473.

To all whom it may concern:

Be it known that we, HEINRICH HECHT and FERDINAND SCHENKELBERGER, subjects of the German Emperor, and residing at 5 Kiel, in Germany, Feldstrasse 65, respectively, Hansastrasse 76, in the Kingdom of Prussia, have invented certain new and useful Improvements in Subaqueous Sound-Signal Transmitters, of which the following 10 is a specification:

This invention relates to subaqueous sound signal transmitters of all kinds and its object is to increase the intensity of the sounds produced, the distance of sound 15 transmission, and to secure a more favorable relation between the amount of energy expended and the distance of transmission. The invention is based upon the recognition of the fact that the distance to which the 20 sound produced by a subaqueous sound-signal transmitter is transmitted is reduced when gas or air contained in the sound carrying medium is dissociated or eliminated from the medium at the points in the signaling devices where the sounds are produced.

From this discovery a rule for building liquid operated signalling devices may be deduced. This rule is that either the liquid used in the signalling device for sound production should contain no dissociable or dischargeable gas; or the signalling appliances should be built so that any dissociable gas 25 will not be discharged at the points in the signalling devices where the sounds are produced. In this latter case what is required essentially is that the liquid substantially lacks free gas, or expressed in another way substantially retains any gas contained in it. A feature of this invention consists in the 30 arrangement and construction of the means by which the operating fluid is conducted in the sound producing device. Another feature consists in a special arrangement and construction of the transmitter; and 35 another feature involves the use of special air separating devices. A combination of all of these features may be used to accomplish the desired effect but, of course, cases

may arise in which one of these features alone may be found to suffice. 50

In the case of diaphragm transmitters, submarine sound bells and similar kinds of transmitters, in which no flowing water is employed for producing sound, it is sufficient if an amply large and deep tank be employed, into which the sound transmitters are lowered and which is filled with fluid which has been previously freed or is in itself free from gas.

If the transmitter is placed in water and provision is made for an easy renewal of the same at short intervals it is not necessary to completely separate it from the outer water but it will suffice if the gas-less or comparatively gas-less water in the neighbourhood of the transmitter is so arranged that it mixes only slowly with the outer water. Nor is it necessary to provide packings for excluding the air, as the permeation by air of a fluid freed from air proceeds but slowly and the permeation process will be especially sluggish where the air has to penetrate to considerable depths. A packing or air excluding means will however be advantageous in any case and it will 65 be necessary when fluids are employed which are naturally free of gas in order to prevent them from mixing with the external medium.

In the case of transmitters which are operated with flowing water or some other flowing liquid, the working medium employed will preferably be a liquid that is naturally free from gas or is at least poor in gas. In this case it is desirable to provide 80 for a continuous circulation thereof. The operating medium can then be easily kept for a long time free from gas by making the conduit in which the operating medium circulates impenetrable by the exterior 85 medium.

As a liquid naturally poor in gas, oil for example, would come under consideration. For the purpose of freeing a liquid from gas artificially the liquid containing the air or 95 gas may first be converted into an emulsion.

like mixture of gas and water, and this mixture then be separated into its constituent parts. The production of this mixture may be effected in various ways. Use may be 5 made of sudden variations in the cross-section of a conduit or conduits through which the liquid is passed, of nozzles, of bends in the conduit or pipe, or of a fall of the liquid through space when entering a special receptacle. Further, to produce this mixture the liquid may be influenced by a stirring mechanism, for example, by vane-wheels, which act in the manner of a ship's screw. In this case the gas elimination may be extended to a considerable degree, by suitably 10 increasing the velocity of the vane-wheels or altering their dimensions and other constructional conditions.

When once such a mixture of air and gas 20 is present, there is no great difficulty in separating this mixture according to its constituent parts by suitable measures.

Several forms of deaerating devices, such as above-mentioned, are illustrated in the 25 drawings, and will be described more in detail hereinafter.

In order to prevent the dissociation of gas from the operating liquid at or near the point of the signalling device where the sound is 30 produced it is necessary to so construct the sound producing device, for example the siren, that no sudden expansion of the jet of liquid takes place at or near the point mentioned. This sudden expansion would result 35 in a decrease of the pressure to which the liquid is subjected and in a consequent change of its degree of saturation and this would enable the dissolved gases to dissociate themselves from the fluid. The means by which 40 the said sudden expansion of the liquid at or near the point where the sound is produced, is prevented, consists in a construction of the sound producer, such as a siren for example, which ensures the greatest possible 45 intimacy of contact between the moving and stationary parts. This construction forms another feature of the present invention.

It is also important to prevent decrease of 50 pressure of the fluid by suctional action in the intake pipe of the force pump that delivers the water to the siren. The means used for accomplishing this and which forms another feature of this invention consists in a special arrangement of the intake and delivery pipes 55 extending to and from the pump.

It has been found that in submarine sound transmitters, which work with movable parts, for example in the case of sirens, the play between the fixed and the actuated 60 parts arising in the course of the working, for example through wear, forms a source of prejudicial gas discharges and causes a considerable reduction of the effectiveness of the sound transmission. The effect of this play 65 is obviated according to our invention, by the

employment of a special packing pressure that presses the rotor against the stator at the point where the sound is produced. This pressure may be effected continuously while the rotor is in motion or only when the siren 70 is caused to emit a sound.

This measure may be applied to all types of sirens, for example, the drum type, the disc type, etc. Care must, however, be taken that it does not interfere with any other of 75 the desirable properties of the sirens.

The said packing pressure may be effected by special mechanical means such as springs and the like, but the pressure of the operating fluid itself may be advantageously utilized 80 for the said purpose.

In the case of fixed sirens this latter can be effected without any constructional difficulties being encountered.

In general the construction may be such 85 that the pressing of the rotor against the stator at the point where the sound is produced is effected either only during sounding, or continuously. A disadvantage of 90 sirens of the former kind is that when the sound control valve is shifted from "Silence" to "Sound," the rotor shaft, in consequence 95 of the play between the rotor and the stator, does not immediately shift over to the one side so as to cause an intimacy of contact between the active portions of the rotor and stator, but instead shifts over after a series 100 of oscillations have first taken place. When these oscillations occur the escape of gas from the working water may take place with the accompanying disadvantages which have been hereinbefore pointed out. In any case the sound will not be as pure 105 as it would be if the position of the rotor shaft were continuously the same. In general the form of construction is preferable in which the onesided pressure of the rotor against the stator is continuous.

The intimacy of contact by a preponderance 110 of pressure may also be effected in cone and ball sirens, as these types of siren are to be regarded as intermediate forms between drum and disc sirens. The one or the other of the methods explained above will be employed according as the particular type 115 under consideration approximates more nearly the one or the other fundamental type.

The invention is explained with reference 120 to a number of practical forms shown in the drawings.

Fig. 1 is a diagrammatic illustration of a 125 siren installation in which the siren is operated by a gasless liquid contained in a closed circuit.

Fig. 1^a is a diagrammatic illustration of a 130 siren installation embodying most of the fundamental features of the invention, in which the siren is operated by water taken in from the outside.

Fig. 2 is a longitudinal section of a drum siren with external rotor and internal valve.

Figs. 3 and 4 are transverse sections of the same on the lines I—I and II—II respectively of Fig. 2.

Fig. 5 illustrates a drum siren with internal rotor and external valve in which it is supposed that the pressing of the rotor against the stator is only effected during sounding.

Fig. 6 shows a transverse section of the same on the line III—III of Fig. 5.

Fig. 7 is a longitudinal section of a drum siren with internal rotor and external valve, in which the one sided pressure is effected continuously.

Figs. 8 and 9 are transverse sections on the lines IV—IV and V—V respectively of Fig. 7.

Fig. 10. illustrates a longitudinal section of a disc siren with internal rotor and external valve.

Fig. 11 a longitudinal section of a disc siren with external rotor and internal valve.

Fig. 12 a longitudinal section of a completely protrudable disc siren with external rotor and internal valve.

Fig. 13 represents a device for eliminating air from liquid by means of drizzle plates and a dripping device cooperating with a vacuum.

Fig. 14 shows another device for eliminating air from liquid, comprising a stirring mechanism and a centrifugal apparatus.

Fig. 15 represents in vertical section an embodiment of our invention in which a diaphragm transmitter is employed.

In the closed circuit arrangement shown in Fig. 1, T is a tank attached to the inner side of the wall *b* of a ship or the like. Through a sleeve T₁, the tank is filled with a gasless or gas-free liquid L₁, for example, with oil. Said liquid passes through a pipe *a*, in communication with the tank T near the bottom of the latter, to the pump *c* by which it is forced through the pipe *d* and introduced into the siren *e* connected with tank T through the sound opening *g* near the top of the tank. The pipe *d* is provided with a gas cock *d*₂ to permit any air contained in the apparatus before it is filled to escape when it is being filled. Since the liquid contents of the tank T are entirely free of gas and are caused to flow through the siren in a closed circuit, the formation of gas bubbles in the siren cannot take place.

In Fig. 1^a all parts of the plant are arranged below the level of the water in which the ship is floating; and the external water, which is used in this plant, enters through intake duct or pipe *a* connected with the ship's side *b*. This intake duct supplies the water to pump *c*. The water is then forced by pump *c* through the delivery or pressure pipe *d* and introduced into

the siren *e*, all changes of the pressure due to expansion by irregularities of the cross-section of the supply pipes being avoided. The intaking capacity of the intake duct is made greater, of course, than the dis-

charging capacity of the siren; and the intake duct *a* is disposed at such a depth in the water as to maintain a head of water over it sufficient to prevent suctional action by the pump *c*.

By these means changes in the pressure of the operating liquid (which changes would cause dissociation of gas from the liquid, or in other words would cause bubbles of gas to appear) are avoided.

The siren is shown in the drawing as a fixed drum siren with an internal rotor directly coupled with the driving motor *f*.

It is connected with the external water through the sound opening *g*.

The water pressed through the siren flows while the siren is sounding, through the sound holes L_r of the rotor R, L_s of the stator S, and L_v of the valve V, and outwards through the sound opening; while, when the siren is silent, it flows through the hole *h* in the bottom I of the siren *e*, through an auxiliary outlet N and the holes S_n in the stator S, and through holes in the valve V which will then be at the point designated by S_v.

Now in order to ensure an intimate contact between the rotor and the stator the rotor has not only been ground into the stator, as this measure alone would not suffice to accomplish the desired effect, but in addition the pressure of the operating water

is utilized for pressing the rotor against the stator, whereby perfect tightness is continuously assured between the working parts where the sound is produced and thus air bubbles are prevented from arising.

This will be seen more clearly from Figs. 2 to 12.

In Fig. 2, R is a rotor which fits like a cap over the stator S and is rotated by a shaft W.

A valve V is arranged in the interior of the stator S, and this valve may be turned by a hollow shaft that surrounds the shaft W and of which only a fragment is shown.

By suitably turning the valve V the siren may be caused to sound or to be silent.

The sound holes L_r of the rotor are distributed in the usual manner around its whole circumference, while in the stator and in the valve the sound holes L_s and L_v as will be seen from Fig. 3 extend only over a part of the circumference.

As shown in Figs. 2 to 4, on the side situated opposite to that of the holes L_s and L_v, slots T_s and T_v are provided in the stator and the valve respectively which slots, as will be seen in Fig. 2, are arranged below the row of sound holes in the rotor and thus allow the water flowing in the direction of the arrow to pass continuously into the space between the rotor

and the stator indicated in the right hand

portions of Figs. 2 to 4, the existence of this space being due to play in the bearings of the rotor. The slots T_s and T_v are of such a size that the passage of working water is possible in any position of the valve, so that the pressing of the left hand internal surface of the rotor against the left surface of the stator is effected continuously. During the sounding operation this one sided pressure is due to the fact that on the left side, where the sound is produced, the working water can flow out of the sound holes into the surrounding medium, so that only a slight resistance is offered to its flow, but on the other side there are no sound holes in the stator that permit a free passage of the water so that the water is forced into the space between the stator and rotor at the right hand side and creates a preponderance of pressure there. It is not possible to prevent some of the liquid from continuously flowing through the sound holes situated above the openings T_s on the side on which the rotor is pressed away from the stator, but nevertheless the resistance offered to the water by the narrow space between the rotor and stator at the right side will be such that sufficient pressure is obtained to ensure the desired intimacy of contact between the sound producing portions of the rotor and stator. When the siren is silent, the water can pass only through the slots T_v and T_s ; the rest of the outlets are closed, so that then also a one sided pressing is effected.

If the lateral pressure is to take place only during the sounding of the siren a number of holes T_s instead of one, must be provided in the stator, which correspond in width and spacing with the similar holes T_v in the valve, in order that when the valve is turned to "Silence" they shall be closed just like the sound holes.

In Figs. 5 and 6 a drum siren with internally situated rotor is shown, and it is supposed that the lateral pressure is only to be effected during the sounding. The same reference marks are adopted for such parts as are similar to parts illustrated in Figs. 2 to 4. The internal rotor R is surrounded first by the stator S , and the stator S is in turn surrounded by the valve V . To obtain a preponderance of pressure on one side in this type of siren is a simple matter, it only being necessary to distribute the sound holes in the stator and in the valve partway around their circumferences. The working water passes through the row of holes L_r into the space between the rotor and the stator on the side situated opposite the sound sector, and effects the tightening on the sounding side by being forced into the space at the opposite side between the rotor and stator. A peculiarity of this siren con-

sists in the novel design of the stator. This design is intended to meet the demand for a protrudable siren with an external valve. If an ordinary standard stator were used, some parts of the externally situated valve would have to be passed through the protrudable stator casing. This difficulty is overcome in the design shown in the Figs. 5 and 6 by the provision of an external stator in addition to an internal stator, the valve being guided between these two stators. The external stator joins on to casing G of the siren, so that this casing has the shape of a pipe with its end bent inwards in the shape of an internal collar.

In Figs. 7 to 9 a drum siren with interior rotor is also shown. In this design, however, a permanent one-sided pressure of the rotor against the stator is provided for. This form of construction differs from that shown in Figs. 5 and 6 inasmuch as an auxiliary outlet N is provided in the rotor, which as will be seen from Fig. 9 consists of a row of holes, the width of which, however (see Fig. 8) is greater than that of the holes L_r , so that a sound cannot be produced by the larger holes. Opposite this outlet N , rows of holes S_n and V_n are distributed over a part of the circumference of the stator and of the valve respectively, these holes being so arranged that in certain positions of the valve the working water can pass out. The upper part of the rotor as well as of the stator and the valve is formed in the usual manner with the alterations according to the invention, as seen from Fig. 8.

The working water thus enters the space between the rotor and the stator and creates a preponderance of pressure there on the side situated opposite the sound sector. If the valve is set at "Sound" the upper openings L_s and L_v are opened and the lower openings S_n and V_n closed. The working water passes through the opening L_r and N into the space between the rotor and the stator and effects the lateral tightening pressure. If the valve is set to "Silence" the upper holes are closed, the openings S_n and V_n however being opened, so that the working water can pass through them, without, however, producing a sound. Moreover, the working water can pass into the space between the rotor and the stator through the openings L_r and N as before, and thus a lateral tightening pressure is permanently assured in this position of the valve also.

In the case of the disc siren with the internal rotor and external valve illustrated in Fig. 10 the application of the idea of the invention is very simple. It is only necessary to arrange the coupling between the motor shaft and the rotor shaft so that the rotor will be pushed downwards into intimate contact with the stator by the pressure

of the water and thus compensate for any wear or spacing which takes place between the two elements. In the drawing, means for ensuring this are not shown, as they will 5 be apparent to any person skilled in the art. From the drawing it will be seen that the rotor R is continually pressed by the working water pressure against the stator, and that the preponderance of pressure tending 10 to maintain the rotor and stator in intimate contact with each other is naturally created.

Fig. 10 further shows a siren in which the construction of the stator is somewhat 15 similar to that of Figs. 5 and 7. It will be seen that here also the valve V is guided between an external and an internal portion of the stator, these portions, being, of course, shaped as required for a siren of the 20 disc type.

In the case of disc sirens with external rotors and internal valves as shown in Fig. 11, the rotor would normally be pushed away from the stator by the pressure of the 25 water. In the example shown this is obviated by the arrangement of a diversion channel U, that branches off from the siren casing and causes the working water to press against a part of the lower surface of the 30 rotor. This or a similar form of construction cannot be employed for protrudable sirens because no irregularities may appear on the casings of protrudable sirens.

If it be required that disc sirens of this 35 type shall be protrudable, the form of construction shown in Fig. 12 may be adopted. The parts employed in the production of the sound are indicated in the same manner as in the other figures. The valve V is 40 actuated by means of a hollow shaft H, which surrounds the driving shaft W of the rotor R, and the opening through which the shaft enters the siren casing is made pressure- and water-tight by means of a 45 stuffing box B. The valve is moved to and fro by a lever G and is thus caused to open and close the sound openings. On its upper extension the shaft W carries a disc A, which rotates on a fixed disc A₂, balls K 50 being introduced between the two discs. The disc A₂ is guided by pins C, which are fixed in the flange F of the siren casing, and rests on springs D, which have a tendency to press the disc A₂ upwards. This 55 pressure is transmitted to the disc A₁, and thereby to the rotor, which, in this way, is pressed against the stator S. In order to enable, for this purpose, the rotor shaft W to move longitudinally, the shaft W is connected to the motor shaft W_m by means of 60 an expansion coupling permitting axial movement and consisting of two discs D_r and D_m provided with pins R₁ and R₂, which are guided in corresponding holes in the

discs D_r and D_m. In this type of siren the 65 rotor is of course kept continually pressed against the stator.

In Fig. 13 a device for eliminating the air from the working water and consisting of drizzle plates and a dripping device is 70 shown which is built into the hydraulic pressure supply pipe between the force pump and the siren. The water conveyed by the pump c, when entering the air eliminating plant is forced through a sieve h 75 where, under certain condition, discharges of gas will occur and a valve i is provided through which these gases may escape. The water then flows over an oblique rippling or drizzling surface k in a broad thin sheet 80 and in so doing liberates a portion of the air contained in it. It then trickles over dripping sieves n in the tank m, this tank being evacuated by a vacuum pump l. The water from which the air has been extracted 85 then passes through the pipe d₁ to the siren or sirens. In an installation of this kind the elimination of the air may be increased to any desired degree by arranging sharp bends in the supply pipe, by causing the 90 water to fall through a space and by increasing the evacuating power of the vacuum. It may in certain cases be necessary to counter-balance the losses of pressure arising in the air-eliminating plant by 95 means of a second pump placed between the air-eliminating plant and the siren. In the case illustrated in Fig. 14 the elimination of the air from the water under pressure is effected by means of a stirring mechanism and a centrifugal device which act on the water successively in separate pressure tanks. In certain cases it may be advantageous to employ a vacuum arrangement in conjunction with these devices.

When the water enters the tank o in coming from the pump c it passes through a sieve h similarly as in Fig. 13 and then comes into contact with a screw p of the propeller type with one, two, or more blades, 100 which, running at a speed that can be regulated suitably to the degree of the air elimination required, causes quantities of gas to be separated from the water in the same manner as this is caused by the screws of a ship when running in a reversed direction and producing the well known emulsion-like mixture of gas and water. The gas which is thus immediately caused to be liberated from the water is allowed to escape 105 through the valve i, while the water and gas still contained in the mixture flow through the pipe n and an opening s into the bottom of a second pressure receptacle t with double walls, in which the emulsion-like mixture is whirled round by a centrifugal device u that separates it into its parts of different specific gravity. The gasless 110

water is thrown by the centrifugal action against the inner wall t_1 of the tank and flows through outlet openings v arranged in this wall in the form of a Venetian blind 5 into the space between the two walls, and from there through the pipe w to the siren. The lighter parts of the mixture, that is the liberated gas, and the water containing a large quantity of gas, collect near the middle 10 of the tank. There they ascend and are conveyed through the pipe z , which is connected with the dome x of the pressure tank t , to another device, for example that shown in Fig. 13, in which the air eliminating 15 process is continued, or they are simply discharged without being put to further use. The deaerating device shown in Fig. 14 is not claimed per se in this application; it is the invention of one of the present co-in- 20 ventors, namely, Heinrich Hecht, and is to be covered in the copending application, Serial No. 54883, filed October 8, 1915.

The centrifugal device employed may be one of the known kind which, with a moderate loss, transforms the work produced in the apparatus in the form of kinetic energy into potential energy.

Referring to Fig. 15, M indicates a housing which is filled with liquid L_2 free from 30 or substantially lacking free gas. The transmitter housing Q is arranged within the housing M on a partition wall E which is closed by a diaphragm whose flange F is mounted against the flange of housing Q 35 and connected with the partition wall E . Within the transmitter housing, any suitable form of electro-magnetic transmitter (not structurally shown) is arranged, to which current is led through the cable X . 40 It is obvious that many other forms of construction may be employed by which the diaphragm transmitter may readily be surrounded by liquid substantially lacking free gas, but the form here shown will serve as 45 an example.

What we claim and desire to secure by Letters Patent is:

1. In a subaqueous sound producing plant, the combination of a casing, a sound producing member in said casing, and liquid substantially lacking free gas in the casing for having sound produced therein by said sound producing member.
2. In a subaqueous sound producing plant, the combination of a casing, a sound producing member in said casing, and liquid in the casing for having sound produced therein by said sound producing member, which liquid substantially retains any gas contained in it during the operation of the sound producing member.
3. A subaqueous sound producer combined with circulation ducts, a source of liquid substantially lacking free gas, said liquid to have sound produced in it by said

sound producer, and means for causing the liquid to flow in said ducts and through the sound producer.

4. A subaqueous sound producer combined with circulation ducts, a source of liquid substantially deprived of its gaseous contents by artificial means, said liquid to have sound produced in it by said sound producer, and means for causing the liquid to flow in said ducts and through the sound 75 producer.

5. In a sound producing plant, in combination, a liquid operated sound producer, a source of substantially gas free liquid, and means for supplying said liquid to said 80 sound producer.

6. In a sound producing plant, in combination, a liquid operated sound producer; means for supplying a liquid thereto, and means for removing gas from the liquid 85 prior to its supply to said producer.

7. A subaqueous liquid-operated siren, combined with the hull of a ship, a pump, an intake duct connecting the water outside the hull to the water inlet of the pump, and a delivery duct for the passage of water from said pump to said siren; the intaking capacity of the intake duct being greater than the discharging capacity of the siren, and the intake duct being disposed at such a depth in said water as to maintain a head 90 of water over it sufficient to prevent suctional action by said pump.

8. In a subaqueous liquid-operated drum-shaped siren, a rotor with sound holes distributed around its entire circumference, a stator with sound holes distributed around a part of its circumference, a valve with sound holes distributed around a part of its circumference, a water passage, means for forcing water through said passage and through the said holes in the stator, the valve and the rotor, and between the parts of the stator and the rotor that are opposite the said sound holes in the stator, so as to cause a spreading at this point and thereby an intimate contact between the rotor and the parts of the stator containing the sound holes at the opposite point.

9. In a subaqueous liquid-operated siren, in combination, a rotor and a stator, and means for causing and maintaining a preponderance of pressure in said siren tending to maintain firm contact of the rotor with the stator at the surface adjacent to the point of sound production.

10. In a subaqueous liquid-operated siren, in combination, a rotor and a stator, and means for causing and maintaining a preponderance of liquid pressure in said siren tending to maintain firm contact of the rotor with the stator at the surface adjacent to the point of sound production.

11. A vibrating diaphragm, a liquid from which all dissolved gases have been re- 120 125 130

moved, and means for retaining said gas-free liquid in contact with said diaphragm.

12. In combination, a vibrating diaphragm, a liquid from which all dissolved gases have been removed, said liquid being adjacent one surface of said diaphragm, and a retaining vessel for maintaining said liquid in place.

13. In combination, a vibrating diaphragm adapted to send out submarine signals, a liquid from which all dissolved gases have been removed adjacent one surface of the diaphragm, and a retaining vessel for maintaining said liquid in place,

15. the outer surface of said retaining vessel being in contact with the liquid through which said submarine signals are to be transmitted.

14. In combination, a vibrating diaphragm adapted to send out submarine signals, a liquid from which all dissolved 20 gases have been removed adjacent one surface of the diaphragm, and a retaining vessel of sound-conducting material for maintaining said liquid in place, the outer surface of said retaining vessel being in contact with the liquid through which the submarine signals are to be transmitted.

In testimony whereof we affix our signatures in presence of two witnesses.
